Atty.

UNITED STATES PATENT OFFICE.

JOHN J. KING, OF BOSTON, MASSACHUSETTS.

PLATE-HOLDER.

1,208,982.

Specification of Letters Patent. Patented Dec. 19, 1916.

Application filed May 31, 1916. Serial No. 100,953.

To all whom it may concern:

Be it known that I, JOHN J. KING, a citizen of the United States, residing at Boston, in the county of Suffolk and State of Massachusetts, have invented certain new and useful Improvements in Plate-Holders, of which the following is a specification.

My invention relates to plate holders for cameras and particularly to improvements in the construction of the plate supports of such holders, the object of the invention being to provide an improved plate support of that type which is constructed with a drip catch into which the fluid from a wet plate drains when the latter is placed in the holder.

It is also the object of my invention to provide an improved support of the character indicated which may be used in a plate holder of ordinary construction and which will protect the latter from the fluid better and more effectively than plate supports as heretofore constructed.

It has heretofore been proposed to, construct the plate supporting bar of a plate holder with a drip catching trough and peculiarly shaped and inclined surfaces for directing the drippings into said trough as shown and described, for example, in the patent to Levy, No. 1,003,475, granted September 19, 1911. The disadvantage to such a construction, however, is that it does not effectually protect the frame of the holder from the fluid for the reason that it is, as a practical matter, impossible to avoid tilting the holder sidewise while handling it with the result that the fluid collected within the trough will all run down to the lower end of the trough and overflow onto the frame so that the latter is soon destroyed.

My invention also has for its object to obviate this objectionable feature.

To these ends my invention consists of a plate support for plate holders embodying the peculiar features of construction and mode of operation set forth in the following description and particularly pointed out and defined in the claims at the close thereof.

In the accompanying drawings: Figure 1 is an elevation of a plate supporting bar constructed in accordance with my invention. Fig. 2 is a plan view of the support shown in Fig. 1, part of the plate holder frame being shown in section at each end thereof. Fig. 3 is a section on line 3-3 of Fig. 1. Fig. 4 is an elevation of the lower

portion of a plate holder for cameras provided with a plate support constructed in accordance with my invention.

Having reference to the drawings, 1 represents the frame of a plate holder for cameras, 2 the usual adjustable top plate holding bar and 3 my new plate supporting bar or rest. The two vertical side bars of the frame 1 are made upon their inner sides with 45 sockets 4 to receive the usual lugs or projections 5 provided at the ends of the plate supporting bar 3 which provides for adjustment of bar 3 lengthwise of the frame as usual, in order to accommodate plates of different 70 lengths.

My improved plate supporting bar 3 is made with an interior longitudinal chamber or trough 6 extending from end to end of the bar except that said trough is closed at 75 its ends by end walls 7. Immediately above the trough 6 the bar is provided with a top wall 8 whose front edge 9 is to the rear of the front wall 10 of the bar so as to leave a slot 11 between said wall and front edge. 80 The front edge 9 of top wall 8 is provided at intervals throughout its length with forwardly projecting lugs 12 that are adapted to support a plate as indicated by dotted lines α in Fig. 3. These lugs 12 extend 85 nearly up to the plane of the outer surface of front wall 10 and to the latter are secured a number of metal plates 13 whose upper ends extend slightly above the plane of the top surface of the plate supporting lugs 12. 90 These plates 13 are quite thin and when the plate α is in proper position on the lugs 12 it rests near its lower edge against the rear sides of the plates and therefore its front sensitized surface is very close to the screen, 95 not shown, which will be immediately in front of wall 10.

The top wall 8 is part of a separate metal strip more or less shaped like an angle iron and having one web thereof secured by 100 screws 14 to the rear wall 15 of bar 3.

In order that the plate α will assume and maintain a position immediately to the rear of plates 13 and over slot 11 the top surface of wall 8 is made so as to slant downwardly 105 toward the front as shown in Fig. 3, and this slanting top surface also serves to cause liquid collecting thereon from the wet plate α to flow by gravity down the same to the slot 11 where it falls into the trough 6. 110 It will also be clear that all liquid dripping from the plate α will fall directly through

slot 11 into the trough. The top edge of the front wall 10 is beveled downwardly toward trough 6 so that any drippings landing thereon will be directed by gravity into the trough. It will thus be clear that whatever liquid is shed by the plate after it is placed in the holder either falls directly into the trough or is directed into the same by the slanting surfaces 16 and 17 and consequently none of the liquid can trickle down upon the outside of the bar and eventually reach and injure the frame of the holder.

At the bottom of the trough 6 the interior 15 of the hollow bar 3 is divided transversely by a plurality of partitions 18 which provide a plurality of pockets 19 within which the liquid collects and these partitions serve to prevent the collected liquid from flowing 20 back and forth endwise of the bar when the latter is tilted with the frame in handling the latter. Heretofore most devices of this character have been constructed so as to effectively collect the drippings from the 25 plate but in handling the frame in carrying it to the camera, placing it in the latter, removing it from the camera and carrying it back to the dark room from the camera, the frame would be tilted and the collected 30 liquid could all run down or lengthwise of the bar to one end of the latter and overflow onto the frame. The transverse partitions 18 prevent this occurring when my improved bar is tilted endwise and the operator does 35 not have to exercise nearly so much care in handling the frame as has heretofore been required.

The main portion or body of my improved bar may be an aluminum casting as may 40 also the top wall 8 with its attaching flange. The plates 13 may be made from sheet aluminum.

What I claim is:

1. A plate support formed with a plurality of pockets and provided with means 45 for directing into said pockets the fluid that drips from the plate.
2. A plate support formed with a drip catching gutter and with a plurality of 50 pockets into which the fluid that drips from the plate is directed by said gutter.

3. A plate supporting bar provided at its ends with means for engaging the frame of a plate holder, said bar being formed with a drip catching gutter extending longitudinally thereof and with a plurality 55 of pockets into which the fluid that drips from the plate is directed by said gutter.

4. A plate supporting bar provided at its ends with means for engaging the frame of 60 a plate holder, said bar being formed with a drip catching gutter extending longitudinally thereof and with a series of pockets extending longitudinally thereof into which the fluid that drips from the plate is di- 65 rected by said gutter.

5. A plate supporting bar comprising means for engaging the frame of a plate holder, a drip catching gutter extending longitudinally of said bar, a longitudinal 70 series of pockets into which the fluid that drips from the plate is directed by the gutter, and a plurality of plate rests connected with said bar for holding a plate in position thereon.

6. A plate supporting bar having an inclined top side and comprising means for engaging the frame of a plate holder, a longitudinal drip catching gutter extending outwardly beyond the lower side of the inclined top of the bar, a series of pockets into which the fluid that drips from the plate is directed by the gutter, and a plurality of plate rests connected with said bar and overhanging said gutter.

7. A plate supporting bar grooved longitudinally to form a drip catching gutter and bored transversely to form a plurality of pockets into which the fluid that drips from the plate is directed by said gutter.

8. A plate supporting bar for plate holders grooved longitudinally to provide a drip catching gutter at one side thereof, and bored transversely to provide a plurality of pockets at the bottom of said gutter into 95 which the fluid that drips from the plate is directed by the gutter, and a plurality of plate rests connected with said bar and overhanging said gutter.

In testimony whereof I have affixed my 100 signature.

JOHN J. KING.
